CALIBRATING MEANS FOR PISTON METERS

Alfred L. Grisé, Springfield, Mass., assignor to Gilbert & Barker Manufacturing Company, West Springfield, Mass., a corporation of Massachusetts

Application November 14, 1942, Serial No. 465,599

6 Claims. (Cl. 73—247)

This invention relates to improvements in calibrating means for piston meters, enabling variation of the stroke of the piston to be effected in order to adjust the meter for the discharge of a predetermined measured quantity per cycle of operation.

There are in the prior art many means for the same purpose. In meters using a crank and connecting rod drive between the pistons and shaft, the crank has been made of variable throw. In meters, wherein the pistons act through cam followers on a cam fixed to the meter shaft, the cam has been made of variable throw as shown for example in U. S. Patent No. 2,121,120, granted June 21, 1938, on an invention of Warren H. De Lancey. The necessity for adjusting the throw of such cranks or cams from outside the meter, leads to complicated and expensive structures which it is desired to avoid. For a simple and relatively inexpensive construction, resort has been made to an adjusting screw which is mounted in the cylinder head for adjustment in the direction of the axis of the piston and which is adapted to be engaged by the piston to determine one end of the stroke thereof. One example of this construction is found in U. S. Patent No. 2,091,912, granted August 31, 1937, on an invention of Warren H. De Lancey. The construction has the disadvantage that it is noisy in operation due to the impingement of the piston, while traveling at substantial speed, with the fixed stop.

This invention has for an object the provision of an adjusting screw, operable from outside the cylinder, whereby the cam follower, carried by the piston, can be moved toward or away from the cam on the meter shaft to vary the stroke of the piston.

This arrangement is simple, inexpensive and operable in a commercially satisfactory manner. While the construction involves lost motion between the cam and one of the cam followers, the amount of lost motion is small and the engagement between the follower and cam occurs at the start of the stroke before the piston has acquired much speed with the result that such engagement is not noisy.

The invention will be disclosed with reference to the accompanying drawing, in which:

Figs. 1 and 2 are fragmentary sectional plan and sectional elevational views respectively, of a piston meter having a calibrating means embodying the invention;

Fig. 3 is an exterior end view illustrative of the means for sealing the calibrating means; and

Fig. 4 is a detail view of the adjusting screw of the calibrating means.

In this drawing, the calibrating means has been shown by way of illustrative example in connection with a piston meter of the type shown in De Lancey Patent No. 2,091,912. One of the plurality of cylinders is shown at 5 and two others are shown in part at 6 and 7. These cylinders radiate from a central chamber 8 and they are arranged in opposed pairs. One of the pistons is shown at 9. The two laterally-spaced members, shown in part at 10, are used to rigidly interconnect the piston 9 to the piston in the opposed cylinder, not shown. The two halves 11 and 12 of piston 10 between which the piston leather 13 is clamped, are held together and to members 10 by cap screws 14. The two laterally-spaced members 15 interconnect the two pistons in cylinders 6 and 7. Carried by each piston is 15 a cam follower adapted to engage and drive a cam 16, fixed on a shaft 17 which is mounted in bearings 18 in the upper and lower walls of chamber 8. One of these followers is shown as a roll 19 on piston 9. The other follower, fixed in 20 position relative to members 10, is marked 20. The followers for members 15, also fixed in position 25 thereon, are marked 21. The shaft 17 serves to drive the valve of the meter which controls the admission of liquid to and the discharge 30 of liquid from the cylinders as by way of conduits such as 22. This shaft also drives whatever registering means is used to indicate the amount of liquid passed through the meter.

This invention provides a special mounting of 35 a cam follower, such as 19, and means whereby its position relative to cam 16 may be adjusted with convenience and accuracy from outside the cylinder and with other advantages which will later be described.

The follower roll 19 is rotatably mounted on 40 a stud 23 fixed in one leg of an angle bracket 24. The other leg of this bracket has an outwardly projecting cylindrical hub 25, which is interiorly threaded to receive the adjusting screw shown in Fig. 4. The hub 25 is slidably engaged in a cylindrical bore formed in and coaxially of the piston part 11 and forms, together with the adjacent leg of bracket 24, a nut which can be moved back and forth within limits in the direction of the axis of the piston and radially of cam 16. The first-named leg of angle bracket 24 lies 45 between and slidably engages finished surfaces 26 on the connecting members 10 which prevent the bracket and its nut from rotating.

The adjusting screw is marked 27. It is

formed on the inner end of a rod or shank 28. This rod is axially slidable and also rotatable in the central hub 29 of piston part 11 which hub projects completely through the companion part 12 as shown. The inner end face of this hub 29 is engaged by a flange 30 on rod 28 near the threaded end thereof. The outer face of hub 29 is recessed to form a seat for a spring 31 which encompasses rod 28 and engages, as a second seat, a washer 32 on the rod. A pin 33 in rod 28 prevents outward axial movement of washer 32. The spring 31 serves to push rod 28 outwardly until the flange 30 engages said inner face. The flange when engaged with the last-named face serves as a seal against passage of liquid inwardly through the piston.

For rotating rod 28 and screw 27 from outside the cylinder, a rod 34 and a hand wheel 35, pinned thereto, are provided. The outer end of rod 34 projects outwardly through a hole in the end face 36 of a hollow hub 37. This hub, which projects outwardly from the head 38 of cylinder 6, is bored to receive and rotatably fit an elongated cylindrical head 39 on the rod. This head, the axis of which is aligned with that of rod 28, is provided with a slot 40 extending diametrically therethrough and axially from the inner end face of the head nearly to its junction with rod 34. This slot 40 slidably receives a blade 41 which is formed on rod 28 and which is of approximately rectangular section. The blade 41 can slide back and forth in the slot 40 as necessitated by the reciprocation of piston 9, but it is non-rotatably engaged with head 39, whereby the rod 28 and adjusting screw 27 may be turned whatever the position of the piston may be and whether or not it is in operation.

Packing 42 is provided around the inner end of rod 34 in the space between the outer face of head 39 and the inner face of the end wall 36. A spring 43, encompassing hub 37, acts between the cylinder head 38 and the inner end face of hand wheel 35 to yieldingly urge rod 34 outwardly and compress the packing 42 to prevent leakage around the rod.

For holding handwheel 35 in its various positions of adjustment, a pin 44 is provided and the flange 45 of the handwheel is provided with a circular series of holes 46 through any one of which the pin may be passed. In the cylinder head 38 are two holes 47 in either of which the inner end of pin 44 may be received. The holes 47 are so spaced that when one of the holes 46 registers with one of the holes 47, the other hole 47 lies midway between two other holes 46 (see Fig. 3). The wheel is turned until the desired adjustment is secured. If no one of the holes 46 then registers with either of the holes 47, then the handwheel is turned a slight distance, in one direction or the other, until a hole 46 does register with a hole 47, and the pin 44 is then passed into the two registering holes 46 and 47 to hold the handwheel 35 in adjusted position. No more than one-fortieth of a revolution is necessary to bring a hole 47 into registry with a hole 46. The pin 44 is held in position by passing a wire 48 through a perforation in the pin and through two adjacent holes 46 and then bringing the ends together and fastening them with a lead seal 49.

The general operation of the meter is as usual and is well understood in the art. The pistons, actuated successively by liquid under pressure, act on cam 16 through their followers and rotate the cam to turn shaft 17. The latter actuates a suitable register and also carries a valve

which controls the admission of liquid to, and the discharge of liquid from the several cylinders. Examples of the general operation will be found in the above mentioned DeLancey patents.

5 In the drawing (Fig. 1) the piston 9 is shown dwelling at the outer end of its stroke and the opposed piston connected to it—the one carrying follower 20—is dwelling at the inner end of its stroke. The upper piston, carrying follower 21 is moving downwardly and acting on cam 16 to turn it in a clockwise direction and the lower piston, carrying follower 21 is being driven by the upper piston to discharge liquid. As shaft 17 continues its clockwise movement, liquid will be admitted to 10 the right hand end of cylinder 5 and the left hand end of the opposite cylinder will be connected to discharge. Piston 9 will then move to the left as will also the piston which is connected thereto. The initial movement of the piston will take up the clearance between the follower 19 and cam 16 without acting on the cam. Then the cam 16 will be driven by roll 19 and the piston will move over a distance equal to the fixed stroke of the piston in cylinder 6 or 7. The 15 result is that piston 9, and the opposed piston connected thereto, each move over a stroke greater than said fixed stroke by the amount of the clearance between follower 19 and cam 16. If this follower 19 is moved to the right by the 20 adjusting screw 27, this clearance will be increased and the stroke of the pistons will be increased. If follower 19 is moved to the left by screw 21, the clearance will be decreased and the stroke of the pistons will be decreased. If follower 19 is adjusted until it engages cam 16, the 25 stroke of piston 9 and its companion connected piston will equal the fixed stroke of either of the pistons in cylinders 6 or 7.

It will be noted that the piston 9 when moved to the left will cause follower 19 to be moved against cam 16 and that later in the cycle, the follower 20 will be moved by its piston against the cam. An impingement occurs twice during each cycle of operation of the meter whenever the follower 19 is in any of its various adjusted positions other than its extreme left hand position. However, in each case, the impingement occurs at the start of a piston's stroke and before the piston has acquired much speed. Consequently, no substantial noise occurs, as is the case with prior art devices, when the piston engages a stop in the cylinder head near the end of its stroke and while moving at substantial speed.

55 The position of the follower 19 may be varied at any time during the stroke of piston 9. It may be varied also even while the piston is in operation. With the pin 44 removed, one simply turns handwheel 35, which rotates rod 34 and also rod 28 because these rods are non-rotatably engaged by means of the blade 41 and slot 40. Thus, screw 27 is turned to move nut 25 and roll 19. As the piston moves back and forth, the blade 41 moves back and forth in slot 40 without becoming disengaged, whereby a connection between the two rods is maintained for the purpose of turning the adjusting screw.

The invention provides a simple and relatively inexpensive construction whereby the stroke of a piston meter can be varied for the purpose of calibrating the meter. The construction is characterized in that it is not noisy in operation and in that it is operated easily and conveniently and effectively.

What I claim is:

1. In a meter of the type wherein fluid under pressure is admitted to and discharged from a cylinder to reciprocate a piston carrying a cam follower which engages and drives a cam on the meter shaft, stroke-adjusting means comprising a support for said follower mounted on the piston for movement toward and away from the cam, adjustable connecting means between said support and piston including interengaged nut and screw elements, one such element being rotatably mounted in the piston and held against movement in the direction of its axis and the other such element being fixed to said support and mounted for movement in the direction of its own axis and held against rotation about such axis, and means operable from outside said cylinder for turning the rotatable element.

2. In a meter of the type wherein fluid under pressure is admitted to and discharged from a cylinder to reciprocate a piston carrying a cam follower which engages and drives a cam on the meter shaft, stroke-adjusting means comprising a screw having a shank mounted in the piston for rotation about its axis and normally held against sliding movement in the direction of such axis, a nut threaded on the screw and having a part which carries said follower, said nut mounted on the piston for sliding movement in the direction of the axis of the screw and held against rotation, and means operable from outside said cylinder for turning said screw.

3. In a meter of the type wherein fluid under pressure is admitted to and discharged from a cylinder to reciprocate a piston carrying a cam follower which engages and drives a cam on the meter shaft, stroke-adjusting means comprising a support for said follower mounted on the piston for movement toward and away from the cam, adjustable connecting means between said support and piston including interengaged nut and screw elements, one such element being rotatably mounted in the piston and held against movement in the direction of its axis and the other such element being fixed to said support and mounted for movement in the direction of its own axis and held against rotation about such axis, and a rotatable member mounted in the head of the cylinder and operable from outside the cylinder, said rotatable element and said rotatable member mounted with their axes in alignment and being slidably but non-rotatably interengaged, whereby the rotatable member can turn the rotatable element in any position of the piston.

4. In a meter of the type wherein fluid under pressure is admitted to and discharged from a cylinder to reciprocate a piston carrying a cam follower which engages and drives a cam on the meter shaft, stroke-adjusting means comprising a screw having a shank mounted in the piston for rotation about its axis and normally held against sliding movement in the direction of such axis, a nut threaded on the screw and having a part which carries said follower, said nut mount-

ed on the piston for sliding movement in the direction of the axis of the screw and held against rotation, a member rotatably mounted in the cylinder head and operable from outside the cylinder, said member and said shank having telescoping parts providing for relative axial sliding movement throughout the stroke of the piston and for a relative non-rotatable connection, whereby the screw may be turned from outside the cylinder in any position that the piston may assume in its stroke.

5. In a meter of the type wherein fluid under pressure is admitted to and discharged from a cylinder to reciprocate a piston carrying a cam follower which engages and drives a cam on the meter shaft, stroke-adjusting means comprising a screw having a shank extending through the piston and mounted therein, for rotation about its axis and normally held against sliding movement in the direction of such axis, a flange on said shank adapted to abut one face of the piston, a spring on the shank acting against the opposite face of the piston to hold said flange against the first-named face, a nut threaded on the screw and having a part which carries said follower, said nut mounted on the piston for sliding movement in the direction of the axis of the screw and held against rotation, a member rotatably mounted in the cylinder head and operable from outside the cylinder, said member and said shank having telescoping parts providing for relative axial sliding movement throughout the stroke of the piston and for a relative non-rotatable connection, whereby the screw may be turned from outside the cylinder in any position that the piston may assume in its stroke.

6. In a meter of the type wherein fluid under pressure is admitted to and discharged from a cylinder to reciprocate a piston carrying a cam follower which engages and drives a cam on the meter shaft, stroke-adjusting means comprising a screw having a shank mounted in the piston for rotation about its axis and normally held against sliding movement in the direction of such axis, a nut threaded on the screw and having a part which carries said follower, said nut mounted on the piston for sliding movement in the direction of the axis of the screw and held against rotation, a member rotatably mounted in the cylinder head and having a portion of reduced diameter extending out of said head and forming a shoulder located within the head, a manually operable actuator on said portion, packing within the head around said portion and adapted to be compressed by said shoulder, a spring acting to move said member and portion to compress said packing, said member and said shank having telescoping parts providing for relative axial sliding movement throughout the stroke of the piston and for a relative non-rotatable connection, whereby the screw may be turned from outside the cylinder in any position that the piston may assume in its stroke.
